CONVERSION OF HYDROCARBON OILS

Filed April 7, 1937

UNITED STATES PATENT OFFICE

2,130,313

CONVERSION OF HYDROCARBON OILS

Joseph M. Barron, Port Arthur, Tex., assignor to
The Texas Company, New York, N. Y., a corpora-
tion of Delaware

Application April 7, 1937, Serial No. 135,377

7 Claims. (Cl. 196-9)

This invention relates to conversion of hydro-
carbon oils and has to do particularly with the
cracking of hydrocarbon oils to lower boiling
products, such as gasoline, in a cracking operation
5 involving the principle of gas reversion.

In the cracking of higher boiling oils to lower
boiling products, it has been found advantageous
to carry out the cracking of the heavier oils in
the presence of normally gaseous hydrocarbons.
10 One source of such normally gaseous hydrocar-
bons is the gases evolved in the cracking opera-
tion. In order to recover the normally gaseous
hydrocarbons evolved in the cracking process, it
is advantageous to use a scrubbing medium which
15 may conveniently be charging stock to the system.
This charging stock enriched with the normally
gaseous hydrocarbons may then be charged to the
cracking zone wherein the higher boiling oil
undergoes cracking in the presence of gaseous
20 hydrocarbons. During the cracking operation
the normally gaseous hydrocarbons enter into the
conversion reactions to produce increased amounts
of the desired low boiling liquid hydrocarbons.

In accordance with the present invention, the
25 feed stock enriched with the gaseous hydrocar-
bons may be charged to the heating and cracking
zone and preferably the gaseous hydrocarbons are
separated from the enriched feed stock and the
gaseous hydrocarbons so separated charged to an
30 intermediate point in the cracking zone.

More particularly, according to the invention, it
is preferred to employ a cracking operation in
which the cracking is carried out in zones of heat-
35 ing and soaking. A feature of the present in-
vention is mixing an oil enriched with the gaseous
hydrocarbons recovered from the cracking
system with a condensate recycle stock and the
flashing from this mixture the normally gaseous
40 hydrocarbon fraction which is returned to the
soaking zone of the cracking system.

The invention will be more fully understood
from the following description taken in connec-
tion with the accompanying drawing which shows
in elevation a sketch of one form of apparatus
45 for carrying out the process.

In the following description an apparatus is
described for carrying out the process in which a
clean and dirty recycle stock are cracked in sep-
50 arate coils, the two streams combined and passed
through a soaking zone. It is to be understood,
however, that the principle of the present inven-
tion may be applied to any well known type of
cracking operation, for example one operating on
55 a recycle basis in which the cracking is carried

out in cracking and soaking zones, such as coil
and drum.

Referring to the drawing, numeral 1 represents
the cracking furnace, 2, 3 and 4 a series of soak-
ing drums, 5 a primary fractionator, 6 a second-
ary fractionator, 7 a naphtha stabilizer and 8 a
gas absorber. The furnace is shown as a vertical,
circular type and the soaking drums as a series
of vertical stills. It is to be understood, how-
ever, that any well known type of furnace may
be used and one, or more than one, reaction
drum may be employed. The furnace contains
two coils, 10 and 12, for cracking the clean oil
and dirty oil respectively. It is intended that
the invention shall not be limited to a two-coil
cracking system but instead a single coil may
be used, for example as in semi-clean or super-
clean circulation; the semi-clean in which the re-
cycle stock and charge are cracked in the same
coil; the super-clean in which the distillate re-
cycle stock is cracked in a separate coil and then
combined with the dirty recycle stock or mixture
of charge and dirty recycle stock and sent to a
soaking or coking zone. In any of these types
of operation the recycle stock may be combined
with the rich oil containing normally gaseous
hydrocarbons, preferably recovered from the sys-
tem, the mixture flashed and the normally gaseous
hydrocarbons introduced into the soaking
zone.

In practicing the invention with the apparatus
shown, the charging stock, such as gas oil, crude
oil, naphtha, crude residuum etc., is introduced
through the line 15 and forced by the pump 16
through the line 17 to a heat exchange coil 18, 35
located in a reflux condenser section 19, superim-
posed on the secondary fractionator 6. A por-
tion or all of the charge may be by-passed
through the line 20 and conducted through the
line 21 to the top of the absorber 8 as a scrub-
bing medium.

In some cases it may be desirable to use a
second oil, such as a special gas oil or naphtha,
as an absorbent or scrubbing medium, and in this
case such an oil would be introduced through the
line 22 and forced by the pump 24 through the
line 21 to the absorber 8 by suitable regulation
of the valve 25 in the line 21 and the valve 26
in the line 27. A portion of this oil may be sent
directly through the line 27 to the heat exchange
coil 18.

The gases introduced into the absorber 8 are
principally butane and lighter and may be de-
rived from the stabilizer 7 or accumulator 30,
both of which communicate with the absorber

8 through the lines 31 and 32 respectively. These gases are scrubbed countercurrently with the oil introduced through the line 21 and the desired gases absorbed in the scrubbing medium while the unabsoed or fixed gases are released from the top of the absorber through the line 34. It is intended that the C₃ and C₄ hydrocarbons and a portion of the C₂ hydrocarbons, if desired, may be absorbed. The rich oil is withdrawn from the bottom of the absorber through the line 35 in which is located a pump 36, and combined with the remainder of the charge in the line 17, if any, and the mixture conducted to the heat exchange coil 18, where they pass in indirect heat exchange 15 with the cracked vapors from the system.

The oil is conducted from the coil 18 through the line 40 to another heat exchange coil 41, located in the lower portion of the fractionator 6. The preheated oil is transferred from the coil 41 20 through the line 42 to a flash drum 44. In the coil 18 the oil is preheated to a temperature of about 300-325° F. and further heated in the coil 41 to a temperature of 450-500° F. There is also drawn into the flash drum 44 a dirty cracking 25 or recycle stock from the primary fractionator 5 through the line 45, in which is located a pump 46. The latter oil may be at a temperature of about 830-860° F. The flash drum is maintained under relatively high pressure which may be 400-30 600 pounds per square inch or higher. The pressure may be regulated by the valve 47 in the line 48. It is preferable to regulate the pressure to around 420-450 pounds per square inch and at this pressure gases are released through the valve 35 47 and passed through the line 48 to the entrance of the soaking drum 2. The unvaporized oil in the flash drum 44 is withdrawn from the bottom thereof through the line 50 in which is located a pump 51. Any proportion of this oil may be 40 introduced into the upper portion of the fractionator 5 as a dephlegmating medium through the branch line 52 controlled by valve 53. The remainder of the charge is conducted through the line 54 to the dirty oil cracking coil 12. The 45 temperature of this oil entering the coil 12 is usually around 750-800° F. In the coil 12 the oil is raised to a temperature of about 830-890° F. and then discharged into the line 56 leading to the soaking drum 2.

50 A clean recycle stock is withdrawn from the bottom of fractionator 6 through the line 60 and forced by the pump 61 to the clean oil heating coil 10. A portion of the clean recycle stock may be withdrawn from the line 60 through the bypass line 62, cooled in the cooling coil 63 and the cooled product by-passed through the line 64 to the upper portion of the fractionator 5 as a reflux medium. The recycle stock is heated to a temperature of about 950-1000° F. and then 55 mixed with the hot products from the residuum heating coil 12. The mixture at a temperature of about 900-910° F. is then passed through the line 56 wherein it is mixed with gases from the line 48 and the mixture introduced into the top 60 of the soaking drum 2. The products pass serially through the soaking drums which are connected by lines 66 and 67. About 300-600 pounds pressure, or more, may be maintained on the reaction drums and preferably around 400 pounds 65 pressure. The temperature in the reaction drums may vary considerably but a satisfactory temperature may be about 900° F. on soaking drum 2, about 885° F. on soaking drum 3 and about 870° F. on soaking drum 4. Liquid products 70 collect in the bottom of soaking drum 4 and

these liquids are continuously withdrawn so as to maintain a low liquid level in this drum. The liquid products so withdrawn are discharged through the line 69 by automatic control valve 70 and discharged from the system or further treated, as desired, for example in a tar stripper. 5

The vapors are withdrawn from the drum 4 through the line 72 to the fractionator 5. In the fractionator 5 a heavy condensate is produced and collects with the reflux medium introduced through lines 52 and 64 to form a mixture of dirty oil which is withdrawn from the bottom of the fractionator 5 through the line 45 and forced by the pump 46 into a flash drum 44, the operation of which has been described above. 15 The vapors from the fractionator 5 are withdrawn through the line 74, and conducted to the lower portion of the secondary fractionator 6. In the fractionator 6, substantially all the hydrocarbons of higher boiling point than the desired final distillate are condensed and collected in the lower portion of the fractionator as a clean distillate recycle stock which is withdrawn from the bottom of the fractionator through the line 60, as described heretofore. 20

In order to obtain adequate separation of the vapors, a reflux condenser 19 is shown superimposed upon the secondary fractionator 6. The vapors from fractionator 6 pass from the upper portion of the fractionator 6 through the vapor line 75 to the reflux condenser, wherein additional reflux condensate forms and flows from the reflux condenser through the line 76 into the top of the fractionator 6. The vapors containing the motor fuel hydrocarbons are withdrawn 35 from the top of the reflux condenser through the vapor line 78, condensed in the condenser 79 and the condensate collected in the accumulator 30. The accumulator 30 may be maintained under about 150-200 pounds pressure and uncondensed 40 vapors and gases are released through the valve controlled line 32 and conducted to the absorber 8, the operation of which has been described heretofore.

The condensate in the accumulator 30 is withdrawn through the liquid draw-off line 81 and introduced into the lower portion of the stabilizer 7. In the stabilizer the undesired normally gaseous hydrocarbons are stripped from the distillate. The liquid collecting in the bottom of 50 the stabilizer comprises stabilized naphtha which is drawn from the bottom of the stabilizer through the line 82. The normally gaseous hydrocarbons, including C₃ and C₄ hydrocarbons, are conducted from the top of the stabilizer through the line 55 31 to the lower portion of the absorber 8.

In practicing the invention charging a crude residuum, and recycling about 35% by weight of C₃ and C₄ hydrocarbons, a 7% increase in naphtha yield may be obtained. 60

The present invention provides a convenient means of obtaining the benefits of gas reversion without substantial loss in fresh charge capacity and no materially increased tendency toward coke formation in the heating coil. 65

Obviously many modifications and variations of the invention, as hereinbefore set forth, may be made without departing from the spirit and scope thereof and therefore only such limitations should be imposed as are indicated in the appended claims. 70

I claim:

1. A process for the conversion of hydrocarbons to produce motor fuel, which comprises subjecting a higher boiling hydrocarbon oil to crack- 75

ing conditions of temperature and pressure whereby lower boiling hydrocarbons are formed, passing the cracked products to a soaking zone to undergo further conversion, separating the 5 cracked products into vapors and residuum, fractionating the vapors to separate therefrom a fraction containing insufficiently cracked hydrocarbons, passing said insufficiently cracked hydrocarbons to a flashing zone, also introducing 10 into said flashing zone charging stock containing normally gaseous hydrocarbons, separating in the flash zone a vapor fraction containing said normally gaseous hydrocarbons, passing said vapor fraction to the soaking zone and charging 15 the residual fraction from the flashing zone to the cracking operation.

2. A process for the conversion of hydrocarbons to produce motor fuel, which comprises subjecting a hydrocarbon oil to conversion temperatures in zones of heating and soaking, separating the cracked products into vapors and a residual oil, dephlegmating the vapors to form a reflux condensate and an uncondensed vapor fraction, transferring the reflux condensate to a flashing 25 zone, fractionating the uncondensed vapor fraction to separate the motor fuel from normally gaseous hydrocarbons, absorbing the higher boiling portion of said normally gaseous hydrocarbons in a hydrocarbon oil, introducing said 30 hydrocarbon oil and absorbed gaseous hydrocarbons into said flashing zone, separating in said flashing zone normally gaseous hydrocarbons, passing said normally gaseous hydrocarbons so separated to the soaking zone and charging 35 oil from the flashing zone to the cracking zone.

3. A process for conversion of higher boiling hydrocarbon oils into lower boiling hydrocarbon oils, comprising subjecting the oil to cracking 40 temperatures in zones of heating and soaking, separating the cracked products into vapors and a residual oil, fractionating the vapors to form a dirty cracking stock, a clean recycle stock, a motor fuel condensate and normally gaseous hydrocarbons, returning the clean recycle stock 45 to said heating zone, scrubbing the normally gaseous hydrocarbons with a lean absorbent oil to absorb the higher boiling constituents of said normally gaseous hydrocarbons, combining the resultant rich absorbent oil with said dirty cracking stock, flashing from the resulting mixture a fraction containing normally gaseous hydrocarbons, introducing said fraction containing 50 normally gaseous hydrocarbons into said soaking zone, subjecting the bottoms from the flashing operation to cracking temperatures and introducing the cracked product into said soaking zone.

4. A process for the conversion of hydrocarbons to produce motor fuel, which comprises subjecting hydrocarbon oils to a conversion operation whereby motor fuel hydrocarbons are formed, separating the products of reaction into vapors and residuum, fractionating the vapors to sep-

5 arate a reflux condensate, commingling said reflux condensate and fresh charge containing normally gaseous hydrocarbons, flashing said mixture to form residual oil and a fraction containing normally gaseous hydrocarbons, charging 10 said residual oil to the conversion operation and introducing said fraction containing normally gaseous hydrocarbons into the conversion operation at an intermediate point thereof.

5. A process for the conversion of hydrocarbons to produce motor fuel, which comprises subjecting hydrocarbon oils to a conversion operation whereby motor fuel hydrocarbons are formed, separating the products of reaction into vapors and residuum, fractionating the vapors to 15 produce a recycle stock and an unstabilized motor fuel, subjecting said unstabilized motor fuel to stabilization thereby forming a stabilized motor fuel and normally gaseous hydrocarbons, contacting said normally gaseous hydrocarbons with 20 a cracking stock thereby absorbing higher boiling constituents of the normally gaseous hydrocarbons, preheating the resultant enriched cracking stock with the aid of heat from said recycle stock, flashing the preheated product to form a 25 volatile fraction containing normally gaseous hydrocarbons and a residual oil, charging said recycle stock and residual oil to said conversion operation and introducing said volatile fraction containing normally gaseous hydrocarbons into 30 the conversion operation at an intermediate point thereof.

6. A process for the treatment of hydrocarbons which comprises preheating a charging stock containing normally gaseous hydrocarbons, flashing the preheated mixture to produce a volatile fraction containing normally gaseous hydrocarbons and a residual oil, subjecting said residual oil to a conversion operation in zones of heating and soaking to form motor fuel products, passing 40 said volatile fraction containing normally gaseous hydrocarbons to said soaking zone, separating from the reaction products a recycle stock, subjecting said recycle stock to cracking temperatures and introducing the hot products into the 45 soaking zone.

7. A process for the treatment of hydrocarbons which comprises scrubbing residual gases from the conversion of hydrocarbon oils with a cracking stock thereby enriching the cracking 50 stock with normally gaseous hydrocarbons, separating the enriched cracking stock into a volatile fraction containing normally gaseous hydrocarbons and residual oil, subjecting the residual oil to conversion in zones of heating and soaking, 55 charging said volatile fraction to the soaking zone, separating from the products of reaction a recycle stock, a motor fuel fraction and residual gases, heating the recycle stock to cracking temperatures, passing the hot products to the soaking zone, and conducting the residual gases to the first mentioned scrubbing operation.

JOSEPH M. BARRON.
